UNITED STATES PATENT OFFICE.

MICHAEL SCHREINER, OF BROOKLYN, NEW YORK.

TOILET-RACK.

1,129,363.

Specification of Letters Patent. Patented Feb. 23, 1915.

Application filed January 11, 1913, Serial No. 741,544. Renewed September 10, 1914. Serial No. 861,134.

To all whom it may concern:

Be it known that I, MICHAEL SCHREINER, a citizen of the United States, residing at Brooklyn, in the county of Kings and State 5 of New York, have invented new and useful Improvements in Toilet-Racks, of which the following is a specification.

The present invention relates to racks, stands and toilet article supports, and aims 10 in the production of a combination rack wherein elements of simplicity and durability are obviously displayed.

My invention is more especially used as a supporting rack for toilet articles or the 15 like, and not only assures an efficient support therefor, but also provides a sanitary receptacle for receiving the same.

The sanitary principles of the present device are obvious, inasmuch as the same is 20 constructed almost entirely of glass, and the parts readily detachable for cleansing.

With these and other objects in view my invention relates to such details of construction and in the arrangement and combination 25 of parts as will be hereinafter fully described and specifically pointed out in the appended claim.

In describing my invention in detail, reference will be had to the accompanying 30 drawings wherein like characters denote like or corresponding parts throughout the several views and in which;

Figure 1 is a front elevation of my invention illustrating a number of toilet articles in place thereon. Fig. 2 is a plan view 35 of a supporting disk. Fig. 3 is a view showing certain portions of the rack in side elevation and the other parts in section.

Referring now more particularly to the 40 drawings wherein is shown the preferred embodiment of my invention, the numeral 10 designates the support which is constructed preferably of a vertical strand of heavy tubing, but in view of the fact that other 45 materials may be used, it is to be recognized that I am not limited to this. The lower end of the support is branched and bent as shown at 11, and formed into a pair of diverging arms 12, the latter being enlarged 50 at their extremities as shown at 13 and secured in place upon a supporting structure by such means as shown at 14. While this form of securing means has been illustrated it is apparent that other forms may be em-

ployed when desired. A cup-shaped receptacle 15 is supported upon the support, near its lower end wherein is provided a suitable supporting rack for different toilet articles. In the drawings I have shown a powder box 16 disposed therein for the sake of illustrating the applicability of the device. Further, the upper end of the support is bent as shown at 17 and provided with a horizontally disposed disk 18, the latter having a suitable bearing 19 disposed thereabout, as is apparent. A supporting plate 20 has connection with the bearing 19 as is shown, the latter being comparatively large in relation to the disk 18 and provided with means for supporting tooth brushes and the like, as 70 will be hereinafter mentioned.

By the arrangement set forth above, the plate 20 is allowed to rotate upon the body portion in any desired manner, thus enabling the operator to move the same out of 75 position when extracting the tooth brushes from different points thereon. The plate is provided at its periphery with a plurality of spaced apart cut-out portions 21 which are constricted as shown at 20, and have a 80 lip 23 projecting thereinto as shown. When in place the tooth brushes are first disposed within the cut-out portions 20 and the handles thereof afterward move into the constricted portions 22 thereof. The lip 23 85 projects into the constricted portion, and provides a supporting means which limits the upward and downward movement of the brush, thus securely supporting the same 90 when in place.

Consistent with the above remarks, I have provided a receptacle for covering the upper ends of the brushes, thus rendering the device entirely sanitary. This means comprises a circular glass receptacle 24 disposed upon the plate 20 in the manner shown in Fig. 3 so that the upper ends of the brushes when in place will be entirely covered. The cover is entirely removable, thus allowing the cleansing of both the plate and the interior of the cover and rendering the device sanitary at all times and under all conditions.

The receptacle 24 being annular in cross-section, provides a suitable opening or receptacle wherein may be disposed a glass 25 or other like article. The glass being disposed upon the plate 20, is held in place by the re-

ceptacle and its lateral movement is prevented. This arrangement obviates the supporting of the glass upon an even surface wherein the lateral movement of the same is not prevented.

From the foregoing it is recognized that the device which I have disclosed is very simple in construction and provides a sanitary supporting device for toilet articles 10 which is easy to manufacture and easy to keep clean.

Such changes as are permissible by the subjoined claim may be resorted to without departing from the spirit of my invention.

15 Having thus fully described my invention,

what I claim and desire to secure by Letters Patent is:

In a device of the character described, a support, a plate carried by said support and provided with holding means, and a hollow 20 cover provided with inner and outer spaced apart walls carried by said plate and covering that portion of the plate provided with the holding means and providing a central well in which an article may be supported 25 upon said plate.

MICHAEL SCHREINER.
